UNITED STATES PATENT OFFICE.

DAVID C. PRINCE, OF SCHENECTADY, NEW YORK, ASSIGNOR TO GENERAL ELECTRIC COMPANY, A CORPORATION OF NEW YORK.

PRODUCTION OF ALTERNATING CURRENTS.

Application filed December 14, 1923. Serial No. 680,731.

To all whom it may concern:

Be it known that I, DAVID C. PRINCE, a citizen of the United States, residing at Schenectady, in the county of Schenectady, State of New York, have invented certain new and useful Improvements in the Production of Alternating Currents, of which the following is a specification.

My present invention relates to the production of alternating currents from direct currents, and more particularly to the use of electron discharge devices or valves for that purpose.

The object of my invention is to provide means whereby the efficiency of operation of a system of the type mentioned may be materially improved. A more specific object of my invention is to improve the efficiency of operation of a circuit arrangement of the so-called "push-pull" type in which two valves are operated 180° out of phase.

Circuit arrangements of the specific sort mentioned have been suggested in which it has been proposed that each valve should carry current half of the time and that the wave form of the current in each valve should be substantially rectangular rather than sinusoidal. To assist in bringing about this method of operation the summation current in the two valves has been maintained more or less constant by the use of an inductance in the lead by which direct current is supplied to the system. With the usual type of sine wave oscillating system when high efficiency is sought the current is permitted to pass through the tube during only a small portion of each cycle. The reason for this is that since the plate voltage varies sinusoidally it will be at a minimum for a very short portion of the cycle. During the remainder of the cycle the drop in the valve is necessarily high and the passage of current is accompanied by large losses. It is therefore apparent that in order to obtain a large output the time during which current is permitted to flow must be increased.

A more specific object of my invention is to provide means whereby the losses in the system may be reduced under these conditions.

The novel features which I believe to be characteristic of my invention are set forth with particularity in the appended claims; my invention itself however, both as to its

organization and method of operation will best be understood by reference to the following description taken in connection with the accompanying drawing in which Fig. 1 shows diagrammatically a circuit arrangement whereby my invention may be carried into effect; and Fig. 2 shows some characteristic curves illustrating the relations between various currents and voltages in a system such as that of Fig. 1.

I have indicated in Fig. 1 a pair of electron discharge valves 1 and 2, each having a thermionic cathode 3, an anode or plate 4, and a control electrode or grid 5. The anodes 4 are connected to opposite terminals 6 of an inductive winding 6, the midpoint 7 of which is connected to the positive supply lead 8 of the direct current source. The grids 5 are connected to opposite terminals 9 of an inductive winding 9, which is inductively related to the winding 6, the midpoint 10 of which is connected to the cathodes 3 and to the negative supply lead 11 of the direct current source through a condenser 12 and shunt resistance 13. The frequency of oscillations is primarily determined by means of a capacity 14 in shunt to winding 6. A capacity 15 is also preferably employed in shunt to the winding 9.

In order to obtain a maximum output in the circuit connected to coil 16, which is in inductive relation to coil 6, it is apparent that current should be permitted to flow through one of the valves all of the time. If however, the plate voltage is permitted to vary sinusoidally this results, as pointed out above, in large losses. It is therefore apparent that if the plate voltage can be kept at the minimum value necessary to overcome space charge for the entire period during which current flows in each valve the losses in the valves may be reduced to a minimum. This result may be accomplished to a large extent by the use of an inductive choke 17 in series with the supply lead 8. If this inductance is made sufficiently large it will maintain the current at a constant value regardless of any cyclic voltage change of the plates. If the grid excitation is such as to pass this constant current for one-half cycle through each valve with low plate potential, the remaining drop must be absorbed by the choke 17. The plate voltage is dependent upon the supply voltage, the counter-electromotive force of the oscillating circuit 110

6, 14 and the drop through inductance 17. With the proper proportion of inductance 17 and the proper grid excitation, the plate voltage of the valve which is carrying current may be maintained at the desired low value during substantially the entire period during which current is flowing.

One essential condition for securing this highly efficient voltage relationship is that 10 the valve control does not limit the current during the period when current is flowing. The valve must be either wide open or entirely closed. A consideration of the usual valve characteristics shows that the plate 15 current and the grid current are roughly proportional to each other. From this it would appear that the control system which would produce square blocks of grid current will produce square blocks of plate current at substantially constant plate voltage. 20 Square blocks of grid current can be obtained by the arrangement shown in Fig. 1. Energy is supplied to the grid by the coupling between 6 and 9 and the total grid current is kept more or less constant by an inductance 18. This grid current naturally 25 flows from that grid, which is most positive at any instant, and since the total is constant each grid receives current in square 30 blocks as required.

If inductances 17 and 18 are not large enough to keep the total current constant in the grid and plate circuits, there will be cyclic ripple variations in the current in 35 each of these circuits, as indicated by curves in Fig. 2. In these curves X represents the impressed D. C. potential while A represents the potential of the midpoint 7 of inductance 6, which corresponds to the counter- 40 electromotive force of the oscillating circuit. At points f the counter-electromotive force is zero. There is therefore nothing to prevent a rise in current except the inductance 17. The plate current which is represented by curve B will therefore be rising 45 at these points. To preserve the average the counter-electromotive force at points g and h is higher than the impressed potential X. The plate current b is therefore falling at 50 points g and h.

Similarly, curve C represents electromotive force at the midpoint 10 of the winding 9, which is due to the rectifier action of the grids. Since this potential is depended 55 upon to make the grid current flow and since this potential is zero at points f, the grid current represented by curve D is falling at these points and rising at points g and h. The amplitude of the variation is 60 dependent upon the value of inductance 18.

An inspection of the curves B and D shows that when the plate current is rising the grid current is falling, and vice versa. It is therefore evident that with this arrangement the desired proportionality be-

tween grid current and plate current will not be maintained, and as a result of such variation from the normal the losses will be increased. With the arrangement thus far described therefore it is evident that it 70 is important to make inductances 17 and 18 large enough to prevent any material variation in either the plate current or the grid current during the cycle.

With high frequency and high voltage 75 the design of inductances 17 and 18 becomes increasingly difficult. For instance, if the power factor of the circuit 6, 14 is 10%, the energy current is $\frac{1}{10}$ of the circulating current. The direct current is roughly 80 equal to this energy current so that if the current ripple in the plate circuit is not to exceed 10% of the direct current, then the ohmic impedance of inductance 17 must be 100 times that of 6. The lowest frequency 85 impressed upon 17 is twice the fundamental so that in henries the inductance of 17 must be fifty times that of 6. At radio frequencies and with apparatus of reasonably small size it is extremely difficult to design the 90 inductance 17 so that its natural resonant frequency will be sufficiently above the frequency at which it is required to work. The circuit thus far described is therefore 95 practically limited in its utility to frequencies not above a few hundred cycles.

To overcome the disadvantages above set forth and permit the circuit described to operate successfully at higher frequencies, the inductances 17 and 18 are magnetically 100 coupled. By this means the voltages induced by plate current ripples in 17 may be utilized to cause a grid current ripple similar to that of the plate current. By this means the grid current ripple is shifted 105 180° to the position shown by the dotted curve E. It will be seen that with a grid current corresponding to curve E the grid current is rising and falling in unison with the plate current, and that the desired proportionality between the two currents may be maintained. It is therefore possible even 110 with a considerable ripple in these currents to conform constantly to the conditions of minimum valve loss.

Inductances 17 and 18 in addition to being magnetically coupled may be connected through a capacity 19 shown in dotted line, or the direct current power supply may act as such a coupling capacity. If there 120 should be no oscillations produced in the circuits 6, 14 or 9, 15, it is apparent that inductances 17 and 18 may function as the grid and plate inductances of an oscillating circuit, the capacity coupling of which 125 is furnished by the coils 6 and 9, and by such other parts of the main oscillating circuits as are exposed to one another. This circuit may support parasitic oscillations in which the two valves operate in 130

parallel and the frequency is the natural frequency of the circuits for this condition. The remedy for such parasitic oscillations is to have the fundamental circuit the lower 5 decrement circuit of the two.

While I have shown and described the preferred embodiment of my invention, it will be apparent that it is by no means limited to the particular embodiment shown 10 and described, but that many modifications of the particular apparatus employed, as well as the circuit connections used, may be made without departing from the scope of my invention as set forth in the appended 15 claims.

What I claim as new and desire to secure by Letters Patent of the United States, is,—

1. The combination in a system for producing alternating current of a pair of 20 electron discharge devices each having an anode, a cathode and a control electrode, an inductive winding having its terminals connected to the anode of said devices and an 25 intermediate point connected to a source of direct current through an inductance, a second inductive winding which is inductively related to the first and has its terminals connected to the control electrodes of said 30 devices and an intermediate point connected to the cathodes through a second inductance, the first and second inductances being inductively related to each other.

2. A system for producing alternating 35 currents comprising a plurality of electron discharge devices having plate and grid circuits, a source of direct current for supplying current to the plate circuits, means comprising an inductance for reducing the

variations in the current supplied by said 40 source, means for impressing an alternating current upon the grid circuits and means comprising a second inductance in the grid circuit magnetically coupled to the first whereby such variations as do occur in the 45 supply current are communicated to the current in the grid circuit.

3. A system for producing alternating currents comprising a plurality of electron 50 discharge devices having plate and grid circuits, a coupling between said grid and plate circuits for furnishing excitation to the grids to maintain oscillations, a source of direct current for supplying current to the plate circuits, means comprising an inductance for reducing the variations in the 55 current supplied by said source, and means comprising an inductance in the grid circuit magnetically coupled to the first inductance, whereby such variations of current as may occur in the supply current produce corresponding current variations in the grid circuit.

4. A system for producing alternating 60 currents comprising a plurality of electron discharge devices having plate and grid circuits, a coupling between said grid and plate circuits for furnishing excitation to the grids to maintain oscillations, a source of direct current for supplying current to the plate circuits and a second coupling between the supply circuit and the grid circuits for maintaining substantially constant 65 the proportionality between the currents in the plate and grid circuits.

In witness whereof, I have hereunto set my hand this 13th day of December, 1923.

DAVID C. PRINCE.
